(57) **CLAIM**

The ornamental design for a upper oven door and a lower mini oven door having a window, as shown and described.

DESCRIPTION

FIG. 1 is a front perspective view of an upper oven door and a lower mini oven door having a window therein;

FIG. 2 is a front view thereof;

FIG. 3 is a left side view thereof;

FIG. 4 is a right side view thereof;

FIG. 5 is a top view thereof; and,

FIG. 6 is a bottom view thereof.

The stippling on the lower mini oven door is a transition from a painted glass surface to a transparent window.
